Primary Examiner — John R Yeh(74) *Attorney, Agent, or Firm* — Cheng-Ju Chiang(57) **CLAIM**

The ornamental design for an electric mop, as shown and described.

DESCRIPTION

FIG. 1 is a front perspective view of an electric mop in accordance with my design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the circled portion 8 of FIG. 1;

FIG. 9 is an enlarged view of the circled portion 9 of FIG. 1; and,

FIG. 10 is an enlarged view of the circled portion 10 of FIG. 3.

The broken lines are directed to environment and are for illustrative purposes only. The broken lines form no part of the claimed design.
